(57) **CLAIM**

The ornamental design for a holding tool for plastic-made caps, as shown and described.

DESCRIPTION

FIG. 1 is a front elevational view of a holding tool for plastic-made caps showing our new design;

FIG. 2 is a rear elevational view thereof;

FIG. 3 is a front perspective view thereof;

FIG. 4 is an enlarged partial front elevational view thereof taken along lines 4-4 and 4'-4' shown in FIG. 1

FIG. 5 is an enlarged partial rear elevational view thereof taken along lines 5-5 and 5'-5' shown in FIGS. 2;

FIG. 6 is a cross-sectional view thereof taken along line 6-6 shown in FIG. 4;

FIG. 7 is a cross-sectional view thereof taken along the line 7-7 shown in FIG. 4;

FIG. 8 is an enlarged partial front elevational view thereof taken along lines 4-4 and 4'-4' shown in FIG. 1;

FIG. 9 is a sectional view taken along line 9-9'-9" as shown in FIG. 8.

FIG. 10 is an enlarged partial front perspective view of FIG. 4;

FIG. 11 is an enlarged partial rear perspective view of FIG. 5;

FIG. 12 is a sectional view of FIG. 9 in an environment of use and

FIG. 13 is an enlarged partial perspective view of FIG. 4 in an environment of use.

FIG. 14 is a top plan view of FIG. 3;

FIG. 15 is a bottom plan view thereof;

FIG. 16 is a right side elevational view thereof; and,

FIG. 17 is a left side elevational view thereof.

(Continued)

In the drawings, the evenly-spaced broken lines showing portions of a holding tool for plastic-made caps depict environment and form no part of the claim; the dash-dot-dash lines represent boundaries of the claimed design and form no part thereof.
